(57) **CLAIM**

The ornamental design for an ice cream cone electric toothbrush, as shown and described.

DESCRIPTION

FIG. 1 is a perspective view of an ice cream cone electric toothbrush showing our new design;

FIG. 2 is a top plan view thereof;

FIG. 3 is a first side view thereof;

FIG. 4 is the other side view thereof;

FIG. 5 is a bottom plan view thereof;

FIG. 6 is a top end view thereof; and,

FIG. 7 is a bottom end view thereof.

The broken lines immediately adjacent to the shaded areas represent the bounds of the claim and all of the other broken lines are for illustrative purposes only. None of the broken lines form part of the claimed design.
